(57) **CLAIM**

The ornamental design for a precious stone cut, as shown and described in the accompanying figures.

DESCRIPTION

FIG. 1 is a top view of a precious stone cut;

FIG. 2 is a side view thereof;

FIG. 3 is a bottom view thereof;

FIG. 4 is a top view of a precious stone cut as illustrated in FIG. 1 and rotated 22.5 degrees about the center;

FIG. 5 is a side view of FIG. 4; and,

FIG. 6 is a bottom view of FIG. 4.

All Broken lines showing are for illustrative purposes only, to indicate a surface, and form no part of the claimed design or a specified embodiment thereof.
